UNITED STATES PATENT OFFICE.

WILLIAM PRELLWITZ, OF EASTON, PENNSYLVANIA, ASSIGNOR TO THE INGERSOLL-SERGEANT DRILL COMPANY, OF NEW YORK, N. Y., A CORPORATION OF WEST VIRGINIA.

DISCHARGE-VALVE FOR FLUID-COMPRESSORS.

No. 874,034.

Specification of Letters Patent. Patented Dec. 17, 1907.

Application filed January 18, 1905. Serial No. 241,603.

To all whom it may concern:

Be it known that I, WILLIAM PRELLWITZ, a citizen of the United States, and resident of Easton, in the county of Northampton and State of Pennsylvania, have invented a new and useful Improvement in Discharge-Valves for Fluid-Compressors, of which the following is a specification.

It has been found by practical experience that where the discharge valve seats of fluid compressors are rigidly secured in position in the cylinders, as, for instance, by screwing them into position, the different strains imposed upon the valve seats frequently cause them to work loose and crack or break, thus rendering them useless.

The object of this present invention is to provide certain improvements in the construction, form and arrangement of the several parts of a discharge valve whereby the valve seat is yieldingly held in position within its support thus obviating the liability of the seat to become loosened, cracked or broken.

One embodiment of this invention is represented in the accompanying drawings in which

Figure 1 represents a portion of a fluid compressor cylinder in section with the discharge valve shown in position therein, the discharge valve being in longitudinal central section; Fig. 2 is an inverted plan view of the cage, Fig. 3 is a transverse central section on an enlarged scale of the valve seat, Fig. 4 is a top plan view of the same, Fig. 5 is a detail tail section through one of the ribs which connect the disk portion with the ring portion of the valve seat, Fig. 6 is a vertical central section through the valve proper, Fig. 7 is a bottom plan view of the same, and Fig. 8 is a detail side view of the sliding pin which is held pressed against the valve seat by the valve seat holding spring.

The inner wall of the cylinder is denoted by 1 and its outer wall by 2. The outlet port between the walls is denoted by 3. The outer wall 2 has a hole 4 therethrough of sufficient diameter to permit the insertion and removal of the valve and its seat. The inner wall 1 of the cylinder is provided with a hole 5 therethrough the upper portion of which is enlarged to produce an annular recess 6 surrounding the hole. The valve seat herein shown comprises a central or disk portion 7 and an outer or ring portion 8 connected at intervals by ribs 9. The outer wall of the ring portion 8 of the valve seat has an easy sliding fit with the walls of the hole 5 in the inner wall of the cylinder. This ring portion 8 of the valve seat is further provided with an annular flange 10 which fits within the annular recess 6 around the outer end of the hole 5.

The valve cage is denoted by 11 and it has a flanged head 12 which is bolted or otherwise secured to the outer wall 2 around the hole 4. The discharge valve proper herein shown comprises a ring portion 13 from which uprises an annular shank 14 the outer walls of which are fitted to slide in engagement with the inner walls of the cage 11.

The head 12 of the cage 11 has a centrally arranged depending hollow post 15 the bore of which is open at both ends. This post is provided with an annular shoulder 16 between which and the ring 13 of the valve is interposed a spring 17 for yieldingly holding the valve closed. A pin 18 has an easy sliding fit within the bore of the hollow post 15, the inner end of which pin rests upon the central or disk portion 7 of the valve seat. An adjusting bolt 19 has a screw-threaded engagement with the upper portion of the bore of the hollow post 15, which bolt has a reduced portion 20 which extends down into close proximity to the outer end of the pin 18 when the bolt is in position. A spring 21 is interposed between the screw-threaded portion of the bolt 19 and the outer end of the pin 18 for yieldingly pressing the pin against the valve seat for normally holding the seat in its position within the hole 5. The strength of the spring 21 should be sufficient to exert a greater pressure upon the valve seat than the excess pressure from the cylinder due to the compression of the fluid sufficient to open the discharge valve against the tension of its spring 17. The reduced portion 20 of the bolt 19 is so arranged that even should the spring 21 become broken or weakened it will engage the outer end of the sliding pin 18 and limit its outward movement before the valve seat can lift out of its hole a sufficient distance to permit the escape of pressure around its outer walls.

By permitting the valve seat to have a limited yielding movement the liability of

the seat to work loose and become cracked or broken under the various strains to which it is subjected, is obviated, thereby insuring a material saving in this vital part of the 5 compressor.

It is evident that the valve might be used either vertically or at any other angle with respect to the cylinder and can be used in connection with single-acting or compound 10 compressors. It is also evident that while the engaging walls of the valve seat and hole are shown vertical, they may be made tapered if desired. It is also evident that other means than that herein shown for 15 yieldingly holding the valve seat in its position might be employed without departing from the spirit and scope of this invention; hence I do not wish to be limited to the particular form herein shown, but

What I claim as my invention is:

A valve seat, its support, a discharge valve proper, its cage having a centrally arranged hollow post, a pin for yieldingly holding the valve seat in position, fitted to slide in said hollow post, a spring for holding the pin 25 pressed against the said seat and an adjusting bolt having a screw-threaded engagement with the bore of the said hollow post and arranged as a stop for the pin to limit the movement of the seat away from its support. 30

In testimony, that I claim the foregoing as my invention, I have signed my name in presence of two witnesses, this 16th day of January 1905.

WILLIAM PRELLWITZ.
